(57) **CLAIM**

The ornamental design for an orthotic insole, as shown and described.

DESCRIPTION

FIG. 1 is a perspective view of an orthotic insole showing our new design;

FIG. 2 is a top plan view thereof;

FIG. 3 is a bottom plan view thereof;

FIG. 4 is a left side view thereof;

FIG. 5 is a right side view thereof;

FIG. 6 is a rear view thereof;

FIG. 7 is a front view thereof; and,

FIG. 8 is an enlarged encircled portion view labeled FIG. 8 in FIG. 1.

The dashed lines are included for illustrating environmental structure and form no part of the claimed design.

1 Claim, 8 Drawing Sheets
